UNITED STATES PATENT OFFICE.

JOHN J. NIEDERKORN, OF PORT WASHINGTON, WISCONSIN.

STRAW GUIDER FOR THRASHING MACHINES.

Application filed October 12, 1922. Serial No. 594,155.

To all whom it may concern:

Be it known that I, JOHN J. NIEDERKORN, a citizen of the United States, and resident of Port Washington, in the county of Ozaukee and State of Wisconsin, have invented certain new and useful Improvements in Straw Guiders for Thrashing Machines; and I do hereby declare that the following is a full, clear, and exact description 10 thereof.

This invention relates to straw guides for thrashing machines, and is particularly directed to an attachment adapted to be secured to the blower pipe of an ordinary 15 thrashing machine.

In thrashing machines, as ordinarily constructed, the straw is blown directly from the blower, or discharge, pipe into a pile. It frequently happens that the straw is 20 scattered over a considerable area as the blast of air from the discharge pipe tends to interfere with the formation of a compact pile of straw. In addition to this, there is frequently a considerable amount of dust 25 and dirt in the straw and this is, therefore, blown directly into the pile.

The primary object of this invention is to provide a machine which overcomes the above noted defects and forms a pile of straw in a compact manner and free from 30 dust or dirt.

Further objects are to provide a straw guide which will direct the straw from the blower pipe in any desired direction, which 35 will momentarily retain the straw and allow the dust to be blown away from it, which may be moved to inoperative position, if desired, and which may be readily controlled from a position remote from the end of the 40 blower pipe.

Further objects are to provide a straw guide which is of comparatively light weight, which is strong and durable, which is effective in operation, and which may be 45 cheaply and readily produced.

An embodiment of the invention is shown in the accompanying drawings, in which:—

Figure 1 is a plan view of the blower pipe of a thrashing machine with the straw guide 50 in place.

Figure 2 is a side elevation of the structure shown in Figure 1.

Figure 3 is a sectional view on the line 3—3 of Figure 2.

Figure 4 is a sectional view on the line 55 4—4 of Figure 2.

Referring more particularly to the drawings, it will be seen that the blower pipe 1 has the usual upturned portion 2 adjacent its outer or open end. It is provided with 60 a pair of rigidly attached guide straps 3 which are provided with upturned guiding cams or lugs 4 and 5,—the lugs 5 being in-turned, or turned over towards each other as may be seen from Figure 2, to provide 65 stops whose function will appear later. Supports are slidably carried by these guide straps and comprise bands 6 and 7 and brackets 8 and 9, respectively, secured thereto.

The brackets 9 are provided with bearings 10 within which are journaled the ends of a transverse hollow shaft 11. This shaft carries a plurality of spaced, curved straw guiding fingers 12 which extend beyond and 75 in front of the end of the blower pipe. Arms 13 and 14 are secured rigidly to the shaft 11 in any suitable manner, as by means of clamping rings 15. The central arm extends directly rearwardly and the side arms 80 diagonally and rearwardly. They are all riveted together, as indicated at 16. The fingers 12 are preferably arranged in two rows, as shown, and in staggered relation. They may be supplemented by a transverse 85 bar 17 to which each finger is secured.

The rear supporting member composed of the band 6 and the bracket 8 is secured to the forward supporting member by means of an upper and a lower longitudinal bar 90 18 and 19, respectively, so that they will move in unison. The upper bar 18 is provided with laterally extending ears 20 curved to correspond to the curvature of the blower pipe.

The bracket 8 is substantially of inverted U-shape and straddles the rear end of the arm 13 to guide and limit its motion. A spring 21 is mounted within the bracket 8 and below the arm 13 and urges such arm 100 upwardly.

The means for revolving the device about the end of the blower pipe may comprise a pair of cables 22 and 23 passed around sheaves 24 and 25 secured upon opposite sides 105 of the blower pipe. The forward ends of the cables are attached to the ears 20. It will be seen, therefore, that by properly

manipulating the cables the device may be caused to revolve about the blower pipes so as to point the fingers 12 in any desired direction.

5 It may be found desirable to vary the angularity of the fingers 12 to vary the action of the device. This is readily accomplished by means of a cable 26 passed beneath a pulley 27 and attached to the free 10 end of the arm 13. By drawing upon the cable, the arm 13 is moved downwardly and the fingers 12 correspondingly tilted.

The end of the blower pipe is relatively inaccessible and it therefore is desirable to 15 provide means for controlling the device from a readily accessible point. This is readily accomplished by providing controlling drums 28, 29 and 30 at a point easily within reach of the operator, as for instance upon a lower portion of the blower pipe. The cables 23, 26, and 22 are wrapped around and secured to the drums 28, 29 and 30, respectively. These drums are loosely mounted upon a supporting and 20 operating shaft 31 provided with a crank 32. The shaft is revolvably and slidably carried in bearings formed in brackets 33 and 34 rigidly attached to the blower pipe 1. A screw, or other securing means, 35 is mounted 25 in the bracket 34 and has a reduced portion adapted to enter any of the grooves 36 formed in the shaft 31 to revolvably retain the shaft in any of its positions of adjustment longitudinally of its bearings.

30 The shaft 31 is adapted to selectively operatively engage any of the drums. This is accomplished by providing pins 37 and 38, which are secured to the shaft and project from either side thereof. The pulley 29 is provided with an internal cylindrical cavity 39 within which the pin 37 may 35 freely rotate. The pulley 28 is provided with a slot 40 within which the pin may seat, and by means of which the drum 28 may be operatively coupled to the shaft 31 when the shaft is slid to its extreme left hand position.

The pulley 29 is also provided with a cylindrical cavity 41 and with a slot 42 40 communicating therewith. When the pin 38 is positioned within the cavity 41 it may freely rotate. When, however, it is positioned within the slot 42 it operatively couples the drum 29 and shaft 31.

45 The drum 30 is provided with a slot 43 within which the pin 38 may be positioned to operatively couple the shaft and drum 30.

It will thus be seen that by longitudinally sliding the shaft 31 the pulleys may be selectively, operatively coupled thereto and may be rotated by means of the crank 32.

60 Pawls 44 are carried by a rod 46 carried by the brackets 33 and 34, and cooperate with ratchet teeth 45 formed upon the drums— 65 one pawl being provided for each drum.

The operation of the device is as follows:— When it is desired to shift the straw guide, the shaft 31 is slid into engagement with one of the drums 28 or 30 and the 70 pawl of the drum, which is not engaged, is raised. The crank is then rotated and the appropriate cable 22 or 23 wound upon its drum, the other cable unwinding from the 75 corresponding drum. When the desired position has been attained, the pawl is dropped into place. If it is desired to change the angularity of the fingers 12, the shaft 31 is slid until the drum 29 is operatively coupled thereto. The crank is then rotated to 80 move the cable 26 and correspondingly move the arm 13, thereby rocking the fingers 12.

It will be seen that a straw guide has been provided which may be pointed in any direction desired to correspondingly control the 85 shaping of the straw pile and to prevent the scattering of the straw.

It will further be seen that the angular setting of the fingers may be accurately controlled and adjusted to suit any condition.

90 It will further be seen that the parts may be readily controlled from a remote point easily accessible to the operator.

I claim:—

A straw guide for a thrashing machine 95 having a blower pipe comprising a support slidably surrounding said pipe, a rock shaft carried by said support, spaced fingers projecting from said rock shaft, a lever operatively connected to said rock shaft, a spring 100 positioned between said lever and pipe, a cable attached to said lever, a pair of cables attached to opposite sides of said support, means for guiding said cables, a plurality of drums to which said cables are attached, a manually operable slidably and revolvably mounted shaft loosely passing through said 105 drums, and cooperative means carried by said drums and shaft, whereby when said shaft is longitudinally moved the drums are selectively coupled thereto.

In testimony that I claim the foregoing I have hereunto set my hand at Port Washington, in the county of Ozaukee and State of Wisconsin.

JOHN J. NIEDERKORN.
